UNITED STATES PATENT OFFICE.

FRANK C. CARROLL, OF PAINESVILLE, OHIO.

REGISTER.

No. 829,138.

Specification of Letters Patent.

Patented Aug. 21, 1906.

Application filed December 21, 1905. Serial No. 292,703.

To all whom it may concern:

Be it known that I, FRANK C. CARROLL, a citizen of the United States, residing at Painesville, in the county of Lake and State of Ohio, have invented a certain new and useful Improvement in Registers, of which the following is a full, clear, and exact description, reference being had to the accompanying drawings.

10 This invention relates to a register adapted to be operated from a distant keyboard.

The invention may be organized to register different amounts collected and the total thereof, the number of times the machine is operated, and also the number of times it is operated in some specific manner.

15 The invention is shown in a simple form especially contrived for indicating cash fares of various amounts from five to fifty cents in 20 multiples of five collected on a street-railway car, for also registering the total amounts so collected, for also registering the number of fares collected, and the number of tickets received in payment of fares. It is obvious, 25 however, that the invention is capable of being embodied in machines adapted for other uses—as, for example, for indicating and recording at a central station the amounts paid to clerks in stores and the like.

30 The invention resides in the combinations of parts shown in the drawings and herein-after described, and pointed out definitely in the claims.

In the drawings, Figure 1 is a front view 35 of the device with a part of the face-casing removed. Fig. 2 is a side view of the mechanism when a part of the left end of Fig. 1 has been removed. Fig. 3 is a similar view when the right end of the casing has been 40 removed. Fig. 4 is a fragmentary sectional side view of the segment A, the upper end of one of the levers D, and the stop B, attached to the segment for engagement with the lever.

45 Referring to the parts by letters, A represents a segment pivoted on a horizontal pivot within a casing E, said segment being located as close as convenient to the front plate e of said casing. Near the peripheral 50 edge but on the front face of this segment are symmetrically-spaced figures a, which may be seen one at a time through a window e' in plate e, as shown. The lower indicating character is a letter "T," which may stand for

tickets, while the other characters are "5" 55 and multiples thereof to and including "50." A spring C engages with this segment and acts always to draw it downward. A solenoid-magnet F, whose core f is connected by a link f' with said segment, acts when the 60 magnet is energized to move the segment up in opposition to its spring to its initial position. When it reaches this position, further movement is prevented by the engagement of the segment with a fixed stop J. 65

D D represent a number of swinging metallic levers, all loosely mounted in the same axial line with their upper free ends close to the face of said segment. A small spring d' is associated with each of these 70 levers and exerts its force to swing the free ends of said levers away from said segment and against a stop-bar I, lying close to all of said levers. Associated with each of these levers is an electromagnet G, which is in a 75 normally open circuit adapted to be closed by the operation of a corresponding key K.

The segment, or at least the peripheral edge of it, and that face against which said levers D may engage must be made of conducting material, as metal. Secured to the metallic face of the segment are as many stops B as there are levers D, and they are arranged in such positions that when the segment is swung away from its initial position 80 they are adapted to engage each with its associated lever D when said lever has been drawn against the face of the segment. These stops, however, are made of insulating material, and they are beveled at their lower 85 edges from the face of the disk outward, so that when one of said stops is moved into contact with its associated lever, whose free end was engaging with the face of the segment, said lever is withdrawn from contact 90 with the segment just before the stop engages with the end of the lever, and thereby stops the movement of the segment. 95

Associated with each of the levers D and its electromagnet is a key K. Each of these 100 keys is an electric switch which by its operation closes one of the main circuits, to be presently described and that particular main circuit which includes the associated electromagnet. There are as many of these main 105 circuits as there are levers D and associated electromagnets; but it has only been thought necessary to show one of said circuits because

the others are like it, and one illustration and description will answer for all, and this circuit is shown diagrammatically.

- The electric generator is indicated by II. 5 A wire h leads from one side thereof to each of the electromagnets G. From each magnet a wire h^2 leads to one of the switch members of the associated key. A wire h^3 leads from the other one of said switch members to the solenoid-magnet F and thence back to the generator. Each circuit so made up constitutes what will be termed a "main" circuit. There is, however, a supplemental circuit, which includes a wire h^4 , connecting the electromagnet G with the associated lever D, and a wire h^5 , leading from one side of the generator to a brush M, which is always in contact with the metallic periphery of the segment A.
- 20 When a key is depressed, the main circuit associated with that key is completed, whereupon the solenoid-magnet draws the indicating-segment A back to its initial position. Simultaneously the associated electromagnet 25 G is energized, and it draws the corresponding lever D against the metallic face of the indicating-segment, whereby the supplemental circuit associated with this key is completed. When the operator releases the key, the main 30 circuit is broken, whereupon the spring C becomes effective to draw the segment downward until it is stopped by the engagement of the associated stop with that lever D which had been drawn against the face of the 35 segment. As before stated, the stop is of insulating material and beveled, so that just as the segment is being stopped the stop withdraws the lever from contact with the metallic face of the segment, thereby breaking the 40 supplemental circuit. When the segment is so stopped, it comes to rest in such position that the figure thereon corresponding with the depressed key is opposite the window e' in the front face of the casing. It will remain 45 in this position until a key is again depressed, whereupon the described action is repeated. It is of course apparent that the keys may be placed at any point distant from the other mechanism.
- 50 The several movements of the indicator-segment from its initial position to the various positions in which it is stopped are proportionate to the indicating-figures corresponding with the several stops. These several 55 movements of the indicating-segment may be transmitted by any suitable means to any suitable kind of total-adding mechanism. Such adding mechanism is no part of the present invention, and no attempt therefore has 60 been made to do anything more than show a diagram representing the same and a rotatable ratchet-wheel which is adapted to be moved by the mechanism to be presently explained and which in turn imparts suitable 65 movement to said adding mechanism.

The main adding mechanism is indicated by N, and n represents the ratchet-wheel associated therewith. Mounted loosely upon the same axis with this ratchet-wheel is a lever O, carrying a spring-pawl o for engagement with said ratchet-wheel. 70

A vertically-movable bar P is connected by a link p with the tailpiece a^4 of the segment A, wherefore this bar moves every time the segment moves a distance proportionate to such movement. On this bar is a pin p' , which enters a slot o' in the lever O, whereby the latter is proportionately rocked, with the result that the said ratchet is proportionately turned. 75

Another counting mechanism (indicated by R) is provided for counting the number of tickets. s represents the ratchet-wheel by which this counting mechanism is operated. A pawl V is carried by bar P for engagement 80 with this ratchet. A spring normally holds this pawl in a position where it will not engage with said ratchet when the bar P is moved; but behind the tail of this pawl is a small electromagnet v' , which is fastened to 85 bar P. This magnet is connected in a supplemental circuit associated with the key marked T or, more exactly, with the lever D, associated with the "T" key. This lever has a tailpiece d' , which when the lever is drawn 90 against the segment A is brought against a contact-piece X, which is connected by wire h^8 with one side of magnet v' , the other side of said magnet being connected with the generator by wire h^9 . Whenever this particular 95 key is depressed, the circuit of this magnet will be completed through the lever D, segment A, &c., and will remain completed until the lever is drawn out of contact with the segment as the lever stops said segment. The 100 magnet will draw said pawl into a position where it will engage with said ratchet-wheel. The result will be that in the upward movement of bar P this pawl will advance the ratchet-wheel one step. This movement 105 will of course take place when the segment A moves its shortest distance. 110

In order that the consequent short movement of the bar P shall not have the effect of moving the counting mechanism N, the slot 115 o' in lever O is bent downward near its outer end, so that the outer end of said slot stands vertically when the segment A is in its initial position. The movement of the segment out of this initial position the short distance it 120 does move when the "T" key is depressed causes the bar P to move only as far as will carry pin p the length of the vertical part of the slot o' . Wherefore the lever O is not caused to rock at all during this short 125 movement of segment A.

There is another counting mechanism (indicated by W) whose driving-wheel is the ratchet-wheel w . A spring-pawl w' is secured to the bar P. Wherefore this ratchet- 130

wheel *w* is turned the distance of one tooth every time the bar *P* goes upward, regardless of the distance which said bar travels. The purpose of this counting mechanism *W* is 5 merely to show how many times the register is operated. If the register is used on a street-car, this shows how many passengers were carried.

Having described my invention, I claim—
10 1. In a register, the combination of an oscillating indicator-segment, a series of stops thereon, a corresponding series of independently-movable devices adapted to be severally moved into the path of the respective 15 stops, keys controlling the position of said movable devices, and mechanisms by which the operation of the keys causes the movement of said segment to the initial point and in the reversing direction to bring a stop 20 thereon into contact with the movable devices corresponding with the key so operated.

2. In a register, the combination of a movable indicator, means for moving it to and 25 from its initial position, means determining the distance it shall move from said initial position, magnets which respectively move the indicator in one direction and operate the means for determining how far it should 30 move from its initial position, and a distantly-placed series of keys for controlling the circuits of said magnets.

3. In a register, the combination of an oscillating indicator, a series of stops secured 35 thereto, a series of devices adapted to be moved severally into the path of said stops, a series of keys severally associated with said devices, means controlled by said keys for moving said devices, and mechanisms for 40 moving the indicator to its initial position and away from said position until stopped by the engagement of one of the stops thereon with the movable devices associated with the operating-key.

45 4. In a register, the combination of an oscillating indicator constructed in part of conducting material, a series of insulated stops secured to said indicator, a series of movable devices made of conducting material, a series 50 of electromagnets severally associated with said movable devices and adapted to move them into contact with said indicator, a series of keys adapted to severally close the circuits of said electromagnets, electrical connections between said electromagnets and their associated movable devices, a brush engaging with said indicator, an electric generator and electrical connection between said

brush and electrical connections between 60 said generator and electrical switches adapted to be severally operated by said keys.

5. In a register, the combination of an oscillating indicator, a magnet connected in a normal open circuit and adapted to move said indicator to its initial position, means 65 acting to move said indicator away from said initial position, a series of movable devices adapted to severally stop the movement of said indicator away from the initial position, and a plurality of keys adapted to complete 70 the circuit of said solenoid-magnet and to severally move said stopping devices into operative positions.

6. In a register, the combination of an oscillating indicator, mechanisms for moving it 75 to its initial position and away from said initial position, a series of movable stopping devices, a series of finger-keys controlling the position of said stopping devices, a vertically-movable bar operatively connected with said 80 stopping devices, a ratchet-wheel, a lever concentrically pivoted and having a slot, a pawl carried by said lever for engagement with said ratchet-wheel, and a pin carried by said bar and projecting into said slot. 85

7. In a register, the combination of an oscillating indicator, mechanisms for moving it to its initial position and away from said initial position, a series of movable stopping devices, a series of finger-keys controlling the 90 position of said stopping devices, a vertically-movable bar operatively connected with said stopping devices, a ratchet-wheel, a lever concentrically pivoted and having a slot, a pawl carried by said lever for engagement 95 with said ratchet-wheel, and a pin carried by said bar and projecting into said slot, said slot having its outer end lying at an angle to its main portion and at such an angle that when the segment is in its initial position 100 said angular end of the slot shall occupy a vertical position, a second ratchet-wheel, and a pawl carried by said bar and normally held away from said ratchet-wheel, an electromagnet for drawing said pawl into position 105 to engage with said ratchet-wheel, said electromagnet being connected in a normal open circuit which is adapted to be closed by one of said keys, and counting mechanisms respectively operated by said ratchet-wheel. 110

In testimony whereof I hereunto affix my signature in the presence of two witnesses.

FRANK C. CARROLL.
